UNITED STATES PATENT OFFICE.

HERMAN G. POSSNER, OF PROVIDENCE, RHODE ISLAND.

CARBONATING DEVICE.

Application filed September 13, 1923. Serial No. 662,405.

To all whom it may concern:

Be it known that I, HERMAN G. POSSNER, a citizen of the United States, residing at Providence, in the county of Providence and State of Rhode Island, have invented certain new and useful Improvements in Carbonating Devices, of which the following is a specification.

This invention relates to a beverage carbonator, and has for its object to provide a container for carbon dioxide or carbonic acid gas or some carbonating material, which is adapted to hold the contents under a heavy pressure and to provide a closure member on the discharge end of the container whereby a drinking cup or other receptacle, such as a bottle or jug may be covered or closed while charging the contents thereof, means being provided to control the discharge from the container into the receptacle.

With these and other objects in view, the invention consists of certain novel features of construction, as will be more fully described, and particularly pointed out in the appended claim.

In the accompanying drawings:—

Figure 1 is a side elevation illustrating my improved container as mounted in operating position from a suitable support.

Figure 2 is an enlarged sectional elevation showing the construction of the discharge neck of the container.

Figure 3 is a view showing the cap of the container having a fin or bail formed thereon with an opening to receive a hook or other supporting member.

Figure 4 is an end view of a washer mounted on the end of the stop cock to limit the extent of opening of the stop cock, or valve.

It is found of great convenience to provide a portable container for carbon dioxide or carbonic acid gas under a heavy pressure, adapted for family use, and to provide means whereby the contents may be readily drawn into a drinking cup, or receptacle to charge the contents thereof, which may be water, milk, cider, soda, lemonade, orangeade, or any other beverage, the contents of which will be rendered more palatable by being charged with a carbonating gas, means being provided on the container for covering or closing the receptacle to retain

the charging gas during the charging operation; and the following is a detailed description of one construction by which the desired result may be obtained:—

With reference to the drawings, 10 designates an elongated tube preferably formed of heavy metal, suitable for retaining the charging gas under a heavy pressure. On the upper end of the tube is threaded a closing cap 11 having an upstanding fin or bail 12 pierced at 13, to receive the hook 14, or other device, by which the container may be suspended in operating position. On the lower end of this tube is threaded a valve casing 15 in which a valve or shut off preferably the plug type of valve 16, is rotatably mounted, the same being provided with a small opening 17 which when rotated to the right position will register with the channel 18 through the casing to control the discharge of the contents.

On the larger end of this plug valve is an operating handle 19 and on the smaller squared end 21 of the valve is mounted a washer 20 which is notched as at 22 to engage the stop pin 23 so as to limit the opening and closing rotation of the valve. The lower end of this valve casing is preferably threaded as at 24 and a sleeve or casing 25 is screwed thereonto, the same having a bridge member 26 having an opening 27 therein. The lower end of this sleeve is also threaded as at 28 to receive a correspondingly-threaded end 29 of the closure member 30.

This closure member is preferably formed of rubber and is provided with an enlarged, circular flange 31 of a size to permit of the upper edge of a drinking glass or cup 32 to set against it to serve as a cover for the same and prevent the escape of gas while charging its contents. This closure member is also provided with a downwardly-projecting stopper portion 33 which is adapted to set into the neck 34 of a bottle or jug to close the same during the charging operation of its contents. Instead of forming the closure member entirely of rubber, it may be made of any suitable material and faced with a yieldable material.

I have also provided a tube 35 having its upper end riveted into the bridge opening 27 and extending down through the closure member and projecting a substantial distance

beyond the end thereof to extend into the contents being charged to render more effective the charging operation.

My beverage carbonator is simple and practical in construction and the same is very effective in its operation and by its use any beverage may be charged and rendered more palatable by simply positioning its container beneath this device and permitting a small amount of the contents to flow thereinto.

The foregoing description is directed solely towards the construction illustrated, but I desire it to be understood that I reserve the privilege of resorting to all the mechanical changes to which the device is

susceptible, the invention being defined and limited only by the terms of the appended claim.

I claim:

A carbonating device comprising a carbonating material receptacle with a valved outlet, a casing attached to the outlet and carrying a conducting tube, and a liquid-containing receptacle stopper inserted in a hollow of the casing closely surrounding the conducting tube, the tube extending a distance from the stopper for insertion into a liquid in a receptacle on which the stopper rests.

In testimony whereof I affix my signature.

HERMAN G. POSSNER.
